HONING MACHINE

Charles A. Fulmer, Waukegan, Ill.

Application January 29, 1942, Serial No. 428,759

9 Claims. (Cl. 51—34)

The present invention relates to honing machines and is particularly directed to improvements in limit stops for protecting the reciprocated honing tools, or other machine parts, from damage due to breakdown or failure of the automatic control systems for the reciprocated tools to stop said tools at a predetermined limit of motion within the work to be honed.

An object of the invention is to provide an adjustable and interchangeable limit stop for honing machines having actuating means associated with their honing tools for vertically reciprocating said tools within varying, predetermined limits of motion, so that said machines may be protected when they are set to reciprocate their honing tools between desired limits of motion.

Another object of the invention is to provide an interchangeable limit stop which may, with only minor changes, be fitted to all types of vertical honing machines and is adapted to permit normal operation of the honing machine to which it may be attached becoming effective only in the event of a breakdown of the machine which might otherwise cause damage to the honing tool, a machine part or the work operated upon.

Another object of the invention is to provide a limit stop which may be adjustably positioned at any point along the length of a reciprocating and rotating honing machine spindle and which is adapted to come in contact with the machine table or bushing therefor to prevent the movement of a honing tool attached to the spindle beyond a predetermined position within a cylinder held on said table.

A further object of the invention is to provide a simplified and economical limit stop which may with slight modification be attached to different types of honing machines.

A still further object of the invention is to provide an adjustable and detachable limit stop which when attached to the reciprocated spindle of a honing machine is effectively clamped to said spindle against any normal force exerted thereon and utilizes said force to more securely clamp itself to said spindle.

Another object of the invention is to provide an adjustable limit stop for the general type of honing machines which have actuating means associated with their honing tools for vertically reciprocating said tools within varying, predetermined limits of motion and cooperating with fixed work supporting tables, so that the machine parts and the work may be protected when the lowermost limit of tool travel is set at any verti-

cal position within the tool reciprocating range relative to the fixed position for the work operated upon.

Another object of the invention is to provide a safety limit stop which is adjustable upon the reciprocated, tool carrying spindle of a honing machine to any desired position throughout the length of said spindle, and which acts as a physical means for determining the lower limit of spindle travel without changing the position of a fixed work table and even though the spindle is not near its lowermost limit of motion.

Other objects will be apparent from the following specification and drawings in which:

15 Fig. 1 is a fragmental, side elevational view of a honing machine with my limit stop positioned thereon, parts thereof being shown in cross-section.

16 Fig. 2 is an enlarged cross-sectional view of the 20 limit stop, parts thereof being shown in side elevation.

Fig. 3 is a plan view of the stop shown in Fig. 2.

Fig. 4 is a cross-sectional view taken on line 4—4 of Fig. 2.

25 Fig. 5 is a perspective view of the guide for my stop.

26 A typical honing machine upon which I prefer to attach my limit stop comprises a means for reciprocating a rotating spindle of said machine in 30 a vertical, axial direction. The limits of motion for the working cycle of said spindle may be varied between two maximum limits by adjusting the control mechanism of the spindle reciprocating means. This machine also has provided 35 thereon a rigid or stationary work table adapted to hold the cylinder to be operated on in axial alignment with the spindle and the honing tool depending from the lower end of said spindle.

36 The preferred embodiment of a machine associated with my limit stop consists of a base 8 having a frame 9 mounted thereon, said frame carrying at its upper end a housing 10 which encloses the upper end of a splined spindle 11 and the control mechanism for automatically reversing 40 the movement of the spindle. The spindle is constantly rotated by means of a motor 12 mounted on the frame and connected to said spindle through a bevelled gear 13 meshed with a gear 14 mounted on the motor shaft. The bevelled gear 13 is fixedly mounted for rotation on the bottom of the housing 10 and freely engages the splined spindle 11 so that the spindle has axial movement relative to the said gear. The upper 45 end of the spindle is connected to a piston 15 by means of a shaft 16. The reciprocation of the

piston 15 within its cylinder 17 is accompanied by the alternate introduction of fluid under pressure into the upper duct 18 and the lower duct 19 connected to pressure and exhaust lines 20 and 21, respectively. The lower end of the spindle is connected through universal joint 22 to a suitable honing tool 23 which is in axial alignment with the spindle and is adapted through said connection to be rotated and reciprocated axially within a cylinder 24 to be honed. The cylinder illustrated is opened at both of its ends but the machine shown may also operate upon closed end cylinders for airplane motors in a highly efficient manner. The cylinder 24 is clamped to the underside of a work table 25 which is rigidly mounted to the base 8 of the machine. A hone-bushing 26 is mounted upon the table and positioned in alignment with the cylinder, the honing tool and an opening 27 formed in the table.

The reciprocation of the piston 15 within the cylinder 17 may be accomplished hydraulically by a motor driven oil pump 28 which takes fluid from a sump tank 29 and introduces it under pressure, through a reverse valve 30, to the lines 20 and 21. Fluid under pressure is introduced to the reverse valve 30 through line 31, said valve alternately introducing said pressure fluid to line 20 and then line 21 to reciprocate the piston. To actuate the honing tool between its limits of motion during the working cycle, the reverse valve is automatically moved by a control rod 32 journalled in the housing 10 and connected to the reverse valve by an arm 33. The control rod has for this purpose an upper stop 34 and a lower stop 35 threaded to the control rod and therefore vertically adjustable thereon. The stops are alternately engaged by a shoulder 36 rigid on the spindle 11 to thereby reverse the movement of said spindle and also the honing tool by actuation of the fluid reverse valve 30. The reverse valve may also alternately return discharged fluid to the sump tank 29 through drain line 37 from the lines 20 and 21 when they alternately act as drain lines for the return fluid.

To permit withdrawal of the honing tool from the cylinder to an upper inoperative position, as shown in Fig. 1, the upper limit stop 34 is provided with a reduced body portion and a finger-like extension 350. The stop 34 may be manually rotated to move the finger 350 out of engagement with the shoulder 36; whereupon the spindle would continue its upward movement until said shoulder engaged a stop 360 which, when actuated, stops the machine in any well known manner. It will therefore be understood from the foregoing that the honing machine illustrated functions to reciprocate a rotating honing tool within adjustable predetermined limits of motion.

My limit stop is generally indicated by the numeral 38 and it is adjustably secured to the spindle so that its depending ends just clear the hone-bushing 26 when the honing tool is at its lower limit of motion. The lower limit stop 35 for controlling the lower limit of motion of said honing tool and the stop 38 are both vertically adjustable so that the machine may be adapted to be set for honing a great many types of cylinder blocks having different lengths and the limit stop may always be adjusted to strike the bushing 26 only in the event of breakdown or failure of the reciprocating mechanism of the honing tool. The limit stop effectively prevents movement of the honing tool within the cylinder after breakdown thereby stopping the honing tool

at a predetermined depth to prevent its damaging the closed end cylinder in the event that closed end cylinders are being honed, or if open end cylinders are being honed, then to prevent damage of the base of the machine and the honing tool.

The structure of the limit stop 38 is most clearly shown in Fig. 2 and consists of a split sleeve 39 separated into two independent segments 40 and 41. The spindle has a tapered body portion which has a greater effective thickness at its top portion than at the threaded end 40. It will therefore be seen that the split sleeve tapers downwardly in the direction of movement of the honing tool as it moves from the upper to the lower end of the cylinder 24 to be honed. Surrounding the sleeve is a yoke 42 which has a complementary tapered opening 43 formed centrally therethrough. The opening therefore converges outwardly from a minimum diameter at the bottom thereof to a relatively larger diameter at its upper portion. The lower end of the yoke engages a nut 44 threaded to the lower end of the sleeve 40, said nut, upon tightening thereof, being adapted to draw the sleeve into the opening of the yoke to securely clamp the limit stop 38 to the spindle. The central exterior portion of the yoke has formed therein a peripheral groove 45 for receiving the race 46 of a ball-bearing 47, said race being securely clamped to the yoke by means of a nut 48 threaded to the lower end of the yoke and locked thereto by engagement with the nut 44 when the latter is securely tightened onto the sleeve 40. The nut 48 is provided with annular openings 49 to receive a suitable tightening tool.

A bearing housing 50 is non-rotatable relative to the yoke and the spindle 11 to which it is clamped and consists of an abutment carrying portion 51 which is fastened to the outer race 52 of the ballbearing 47 by means of an annular plate 53 fastened to the upper end of said abutment portion by bolts 54. The inner edge of the plate 53 is provided with an oil retaining ring 55 while the lower circular edge of the abutment portion of the housing also has positioned therein an oil retaining ring 56. The yoke has an integral overlapping portion 57 provided with a peripheral downwardly turned flange which cooperates with a raised inner edge on the plate 53 for preventing dust and other foreign material from entering the bearing. The housing has cast thereon a tail piece 58, the outer end 59 of which is vertically movable in a guide 60 fastened to the underside of the machine frame by bolt 61. The guide 60 has a vertical slot therein in which the end 59 of the tail piece moves to prevent rotation of the housing. The lower surface of the housing is provided with a number of threaded holes 62 in which are threaded the reduced threaded ends of removable abutment shafts 63 depending from the non-rotatable housing 50. These openings are disposed various radial distances from the center of the stop so as to engage the bushing 26 regardless of the diameter of the cylinder being operated upon.

When the abutment stop comes in contact with the hone-bushing 26 on the table due to failure of the oscillating mechanism to reverse the direction of movement of the hone within the cylinder from a downwardly direction to an upwardly one, it will be seen that the spindle and the sleeve carried by it are moving downwardly whilst the yoke 42, through its connection with the abutment shaft 63, tends to remain in a stationary

position thereby tending to force the sleeve 40 into the tapered opening 43 on the yoke 42. This tendency of said parts is similar to that employed by tightening the nut 44 on the sleeve 40 and tends to draw the sleeve 40 further into the yoke thereby increasing the clamping action and more rigidly fastening the stop to the spindle.

To attach the limit stop 38 to the spindle of a honing machine, the honing tool is removed from the lower end of the spindle by disconnecting the upper end of the universal joint 22 from an enlarged portion formed on the lower end of said spindle. The complementary sleeve portions 40 and 41 are then positioned around the spindle and the yoke 42, with the bearing 47, housing 50 and nut 48 in assembled position thereon, is moved over the end of the spindle and around the sleeve portions. Nut 44 is then threaded to the sleeve, and loosely drawn up so as to hold the parts together and the entire stop may then be moved to its desired operative position on the spindle and the nut 44 then tightened to clamp said stop to the spindle. The end 59 of the tail piece 58 is then inserted in the slot of guide 60 and said guide fastened to the machine frame 9 by bolt 61. It will be noted that the opening 43 in the yoke has a diameter greater than the enlarged end of the spindle 11 so that said spindle end can be passed through said opening during assembly of the stop. It is contemplated that said opening be made large enough to pass over a great number of enlarged spindle ends, the thickness of the tapered sleeves being varied to accommodate said yoke opening to various spindle diameters. In other words, in various installations where machines are provided with different spindle diameters, sleeves having different sleeve thicknesses will be used to provide a constant exterior sleeve diameter for cooperating with a standardized opening in the yoke.

What is claimed is:

1. In a honing machine the combination of a work table for fixedly holding a cylinder, a rotating spindle, means for vertically reciprocating said spindle, a honing tool in axial alignment with the spindle and fastened to the end thereof for movement within the cylinder, and an adjustable limit stop fastened to the spindle and comprising a sleeve surrounding said spindle and having a downwardly tapering body, a yoke having an upwardly tapering opening formed therein for receiving the sleeve, means associated with the lower end of the sleeve for contacting the yoke and for drawing said sleeve into said opening to rigidly clamp the stop to the spindle, and abutment shafts carried by the stop for engagement with the work table when the honing tool is in a predetermined position within the cylinder.

2. In a honing machine the combination of a work table for fixedly holding a cylinder, a rotating spindle, means for reciprocating said spindle, a honing tool in axial alignment with the spindle and fastened to the end thereof for movement within the cylinder, and an adjustable limit stop fastened to the spindle and comprising a sleeve having a tapered body surrounding said spindle, a yoke having a tapered opening therethrough for receiving the sleeve, means for drawing said sleeve into the opening to clamp said stop to the spindle, a non-rotatable housing mounted on the yoke, and abutment shafts carried by the housing for engagement with the work table when the honing tool is in a predetermined position within the cylinder.

3. In a honing machine the combination of a frame, a work table on the frame and adapted to fixedly hold a cylinder, a rotating spindle on the frame, means for vertically reciprocating said spindle, a honing tool in axial alignment with the spindle and fastened to the end thereof for movement within the cylinder, a guide on the frame, and an adjustable limit stop fastened to the spindle and comprising a sleeve having a tapered body surrounding said spindle, a yoke having a tapered opening formed therethrough for receiving the sleeve, means for drawing said sleeve into the opening to clamp said stop to the spindle, a non-rotatable housing mounted on the yoke, a tail piece on the housing freely engaged by the guide, and abutment shafts carried by said housing for engagement with the work table when the honing tool is in a predetermined position within the cylinder.
4. In a honing machine the combination of a frame, a work table on the frame and adapted to fixedly hold a cylinder, a rotating spindle on the frame, means for vertically reciprocating said spindle, a honing tool in axial alignment with the spindle and fastened to the end thereof for movement within the cylinder, a guide on the frame, and an adjustable limit stop fastened to the spindle and comprising a split sleeve having a downwardly tapered body for surrounding the spindle, and exterior screw threads formed in its bottom portion, a yoke having an upwardly tapered opening formed therethrough for receiving the sleeve and a groove formed therein concentric with the opening, a bearing in the groove, a housing engaging the bearing, a bearing plate fastened to the housing and adapted to clamp the outer race of said bearing to the housing, a nut on the lower end of the yoke and in engagement with the inner race of the bearing, a clamping nut on the sleeve threads and in contact with the yoke bearing nut, said nut being adapted upon tightening to draw the sleeve into the opening of the yoke to clamp the stop to the spindle, and abutment shafts fastened to the housing and adapted to contact the table when the honing tool is in a predetermined position within the cylinder.
5. In a honing machine the combination of a frame, a work table on the frame and adapted to fixedly hold a cylinder, a rotating spindle on the frame, means for vertically reciprocating said spindle, a universal joint on the end of the spindle, a honing tool fastened to the joint and in axial alignment with the spindle for movement within the cylinder, a guide on the frame, and an adjustable limit stop fastened to the spindle and comprising a split sleeve having a downwardly tapered body for surrounding the spindle, and exterior screw threads formed in its bottom portion, said sleeve having a slightly greater inside diameter at its lower portion than the outside diameter of the universal joint, a yoke having an upwardly tapered opening formed therethrough for receiving the sleeve and a groove formed therein concentric with the opening, a bearing in the groove, a housing engaging the bearing, a bearing plate fastened to the housing and adapted to clamp the outer race of said bearing to the housing, a nut on the lower end of the yoke and in engagement with the inner race of the bearing, a clamping nut on the sleeve threads and in contact with the yoke bearing nut, said nut being adapted upon tightening to draw the sleeve into the opening of the yoke to clamp the stop to the spindle, and abutment shafts fastened to the housing and adapted to contact the table when the honing tool is in a predetermined position within the cylinder.

when the honing tool is in a predetermined position within the cylinder.

6. In a limit stop for honing machines having a tool carrying spindle mounted on the frame thereof for vertically reciprocating and rotating movement relative to a fixed work table the combination of a guide on the frame, a sleeve having a tapered body surrounding said spindle, a yoke having a tapered opening formed therethrough for receiving the sleeve, means for drawing said sleeve into the opening to clamp said stop to said spindle, a non-rotatable housing mounted on the yoke, a tail piece on the housing freely engaged by the guide, and abutment shafts carried by said housing for engagement with the work table when the honing tool is in a predetermined position within the cylinder.

7. In a limit stop for honing machines having a tool carrying spindle mounted on the frame thereof for vertically reciprocating and rotating movement relative to a fixed work table the combination of a guide on the frame, a split sleeve having a downwardly tapered body for surrounding the spindle, and exterior screw threads formed in its bottom portion, a yoke having an upwardly tapered opening formed therethrough for receiving the sleeve and a groove formed therein concentric with the opening, a bearing in the groove, a housing engaging the bearing, a bearing plate fastened to the housing and adapted to clamp the outer race of said bearing to the housing, a nut on the lower end of the yoke and in engagement with the inner race of the bearing, a clamping nut on the sleeve threads and in contact with the yoke bearing nut, said nut being adapted upon tightening to draw the sleeve into the opening of the yoke to clamp the stop to the spindle, and abutment shafts fastened to the housing and adapted to contact the table when the honing tool is in a predetermined position within the cylinder.

8. In a honing machine the combination of a work table for fixedly holding a work piece, a

rotating spindle, means for reciprocating said spindle, a honing tool in axial alignment with the spindle and fastened to the end thereof for operative movement on the work piece and an adjustable limit stop fastened to the spindle and comprising a sleeve having a tapered body surrounding said spindle, a yoke formed with a tapered opening for receiving the sleeve, means for drawing said sleeve into the opening in the yoke to clamp said stop to the spindle, and abutment shafts carried by the stop for engagement with the work table when the honing tool is in a predetermined position relative to said work piece.

9. In a limit stop for honing machines having a tool carrying spindle mounted on the frame thereof for vertically reciprocating and rotating movement relative to a fixed work table and a universal joint between the tool and the spindle, the combination of a guide on the frame, a split sleeve having a downwardly tapered body for surrounding the spindle, and exterior screw threads formed in its bottom portion, said sleeve having a slightly greater inside diameter at its lower portion than the outside diameter of the universal joint, a yoke having an upwardly tapered opening formed therethrough for receiving the sleeve and a groove formed therein concentric with the opening, a bearing in the groove, a housing engaging the bearing, a bearing plate fastened to the housing and adapted to clamp the outer race of said bearing to the housing, a nut on the lower end of the yoke and in engagement with the inner race of the bearing, a clamping nut on the sleeve threads and in contact with the yoke bearing nut, said nut being adapted upon tightening to draw the sleeve into the opening of the yoke to clamp the stop to the spindle, and abutment shafts fastened to the housing and adapted to contact the table when the honing tool is in a predetermined position within the cylinder.

CHARLES A. FULMER.
